UNITED STATES PATENT OFFICE

MARTIN STALSON, OF MINNEAPOLIS, MINNESOTA.

KNOT-TYING DEVICE.

Application filed October 12, 1920. Serial No. 416,373.

To all whom it may concern:

Be it known that I, MARTIN STALSON, a citizen of the United States, and a resident of Minneapolis, in the county of Hennepin and State of Minnesota, have invented a new and Improved Knot-Tying Device, of which the following is a full, clear, and exact description.

This invention relates to a knot tying device and has reference more particularly to a device of this character for forming knots in cord or twine, which is used in tying up packages of letters and the like.

The primary object of the invention is to provide a simple and cheap device for effecting the above recited result and especially a device which is capable of carrying out its intended use with the greatest of efficiency.

The accompanying drawing illustrates a preferred embodiment of the invention and the same will be hereinafter referred to in describing the device in detail.

In said drawing—

Fig. 1 is a perspective view.

Fig. 2 a longitudinal section.

Fig. 3, front elevation looking in the direction of the arrows indicated at 3—3, Fig. 2.

Fig. 4 is a perspective view of a part of the device showing the first step in forming the knot.

Fig. 5 is a similar view showing the second step in forming the knot and

Fig. 6 is a view also similar to Fig. 4 showing the relative position of the cord (in full lines) just before the knot is completed, the dotted lines showing the knot as substantially complete.

According to the proposed preferred form of the device a suitable housing or casing 5 is provided to house the parts. This housing or casing is constructed primarily of a single sheet of metal formed with side walls 6, a top 7, and attaching flanges 8 at the bottom of the side walls. The housing preferably slants along the top as shown with a knot former comprising the needle 9 projecting through an opening in the high end 10 of the housing, the opening being surrounded by a beveled flange 10. For reasons which will be presently mentioned the needle 9 is split or forked, producing two substantially resilient prongs 11 and 12, the

lower ends of which being reduced and confined in an opening by a cotter pin in an operating lever 13 pivoted as at 14 in the low end of the housing. The lever is disposed longitudinally of the housing with its free end extending beyond the end of the high part of the housing.

A coiled spring 15, supported around the post 16, is adapted to maintain the lever adjacent the top 7 of the housing with the needle 9 projecting through the opening 17 therein. The lever may be manipulated to retract the needle within the housing, the spring returning the same to normal position.

Attention is directed to the peculiar construction of the needle. As stated, the same is split producing two substantially resilient prongs, 11 and 12. The inner face of each prong is rounded or convexly curved, so to speak, providing outwardly flaring lips 17, with the abutting faces 18 between the lips and the slot 19. When the needle is projected from the housing, the resiliency of the prongs may be realized to easily slide the cord between the abutting faces 18 and into the slot 19. The frictional contact of the abutting faces, which while permitting the cord to be inserted in and withdrawn from the slot will grip the same sufficiently to cause a slight pull to be exerted in withdrawing the cord from the slot.

The operation is substantially as follows:

The cord to be knotted is held between the thumb and index finger of both hands and looped around the needle (see Fig. 4), one end of the cord, preferably the end A, which is under the end A' is inserted between the lips 17 into the slot 19 (see Fig. 5), the lever 13 is then pressed down whereupon the end of the cord held within the slot 19 will be drawn through the loop by the retraction of the needle, which will also disengage the loop from around the needle. By exerting a pull on the end A' of the cord, the knot thus formed will be drawn tight as the end A of the cord is still held in the slot 19, it is released however when the pull is sufficient to slide it between the abutting faces 18.

From the foregoing it will be seen the operation is extremely simple, at the same time it is positive and little or no skill is required to manipulate the device.

Having thus described my invention, I desire to claim:

1. In a device of the character described, a housing having an opening formed through one wall thereof, a lever fulcrumed at one end within the housing in a plane contiguous to the inner face of the said one wall, said lever having the free end thereof protruding from the housing, a spring disposed within the housing and yieldingly maintaining said lever in a plane extending in contiguous parallel relation to the said one wall of the housing, and a needle secured at its one end to said lever and being of a length to extend through said opening beyond the plane of the outer face of the said one wall when the lever is in the said position in respect to the said wall and to be retracted into the housing when the lever is swung a determined distance about its fulcrum against the action of the spring, said needle having a transverse slot in the normally projecting portion thereof and being split from the slot to the free end thereof, and a beveled flange on the outer face of the said one wall of the housing and in encircling relation to the projecting portion of the needle. 50
2. In a device of the character described, a housing having an opening formed through one wall thereof, a lever fulcrumed at one end within the housing in a plane contiguous to the inner face of the said one wall, said lever having the free end thereof protruding from the housing, a spring disposed within the housing and yieldingly maintaining said lever in a plane extending in contiguous parallel relation to the said one wall of the housing, a needle secured at its one end to said lever and being of a length to extend through said opening beyond the plane of the outer face of the said one wall when the lever is in the said position in respect to the said wall and to be retracted into the housing when the lever is swung a determined distance about its fulcrum against the action of the spring, said needle having a transverse slot in the normally projecting portion thereof and being split from the slot to the free end thereof. 55
3. In a device of the character described, a needle having a transverse slot extending therethrough at an appreciable distance from one end thereof and being split longitudinally from the transverse slot to the said one end, thus producing two prongs at the said one end of the needle, said needle being made of a material having inherent spring qualities, and the inner face of each prong being convexly curved so that the inner faces of the two prongs abut each other intermediately and are spaced apart at their ends, a support provided with an opening through which the needle may move in the direction of its length, and means carrying the needle so that the split end portion of the latter normally projects beyond the end of the opening remote from the said needle carrying means, the latter being movable relatively to the support to withdraw the split end portion of the needle through the opening. 60

MARTIN STALSON.
